UNITED STATES PATENT OFFICE.

EDGAR E. BROSIUS, OF PITTSBURGH, PENNSYLVANIA.

HOISTING-BUCKET.

1,087,105.

Specification of Letters Patent.

Patented Feb. 17, 1914.

Application filed August 14, 1912. Serial No. 715,016.

To all whom it may concern:

Be it known that I, EDGAR E. BROSIUS, a resident of Pittsburgh, Allegheny county, Pennsylvania, have invented a new and useful Improvement in Hoisting-Buckets, of which the following is a full, clear, and exact description, reference being had to the accompanying drawings, forming part of this specification, in which—

10 Figure 1 is a side elevation of a hoisting bucket embodying my invention; Fig. 2 is an end view of the same; Fig. 3 is a detail sectional view, showing certain of the parts; Figs. 4 and 5 are detail views hereinafter 15 more fully described; Figs. 6 and 7 are side elevations showing the bucket in opened positions; Fig. 8 is a plan view of the bucket with the parts closed; and Figs. 9 and 10 are detail views.

20 My invention has relation to hoisting buckets of the clam shell type; and is designed to provide a single line bucket which can be operated with a very much less amount of head room than has heretofore 25 been required.

A further object of my invention is to provide a bucket of this type, which is simple and durable in its construction; and which is capable of exerting a powerful 30 digging action in closing.

The nature of my invention will be best understood by reference to the accompanying drawings, in which I have shown the preferred embodiment thereof, and which 35 will now be described, it being premised, however, that various changes can be made in the details of construction and arrangement of the parts without departing from the spirit and scope of my invention as defined in the appended claims.

In these drawings, the numerals 2 and 3 40 designate the two sections of the bucket, each section having at the inner upper edge portion thereof, at each side, an upwardly 45 projecting bracket arm 4 rigidly secured thereto and formed with a pivot head 5 at its upper end loosely engaging a central transverse shaft 6. In the particular construction shown, this shaft 6 is not continuous, but consists of two stub ends 6^a, with a rigid connecting member 6^b between the sections, and carrying the central shaft section which is marked 6. The shaft may, however, be continuous, and even in the 50 construction shown is to all effects and purposes continuous. The bucket sections are

also swung at their upper outer corner portions, at each end, from their respective links 7 and 8, through the medium of the transverse rods or shafts 9. The links 7 and 8 extend obliquely upward at each end of the bucket in a converging direction, the upper end portions of the links 7 being bent or turned horizontally as shown at 7^a, and the upper ends of the links 8 being pivotally connected to the extremities of these horizontal portions through the medium of the rod or shaft 10.

11 designates upwardly diverging braces connected at their lower ends to the central upper outer portion of one of the bucket sections and at their upper ends to the horizontal portion 7^a of the brace members 7.

12 designates a cross-head, which is movable vertically in the space below the transverse portions 7^a of the links 7, and upon which are journaled the two sheaves or pulleys 13.

14 is the suspending rope or cable, which is provided with the hook block 15 at its upper end for the attachment of a crane hook, and whose lower end portions are carried underneath the respective wheels 13 and are thence made fast to the members 7^a in any suitable manner, as indicated at 16. 80 The cross-head is also provided at each end with a wheel or other bearing 17. Chains 18, or other flexible members, pass over the pulleys, and have their diverging lower ends connected to the brackets or plates 19 secured to the bucket sections.

The cross-head is connected with the central shaft 6 through the medium of a link or toggle device composed of the two members 20 and 21. These two members are 95 hinged or pivotally connected at their adjacent ends, as shown at 22, the other end of the member 20 being sleeved on a shaft 23 carried by the cross-head, and the lower end of the lower member 21 being sleeved on the 100 shaft 6. The lower member 21 has a hub portion 24, formed with a locking shoulder 25, which is adapted to be engaged by a latch hook 26 secured to the shaft 23, as most clearly shown in Fig. 3. This latch 105 member 26 is adapted to be forced into latch engagement with the shoulder 25 by means of a roller 27 which is journaled on a link 28, which is pivotally mounted in a slot 29 of the member 21. The shaft 30 of 110 the roller 27 preferably has slotted bearings, as indicated at 31 in the link 28. The link

28 is connected at its outer end to a pin 35, to the projecting end of which is attached a trip lever 34. Inasmuch as the roller 27 is carried by the toggle members 21, it will be readily seen that as the parts approach near the positions shown in Fig. 3, the roller 27 will forcibly engage the latch 26 to cause its latching engagement with the shoulder 25. An upward pull on the lever 34, however, frees the roller from its holding engagement with the latch. The slotted bearings for the shaft 30 prevent undue bending.

32 is a stop projection on the hub portion of the latch, and which is adapted to contact with the hub portion 24, when the parts are in the position shown in Fig. 3.

The operation is as follows: Fig. 6 shows the positions of the parts after the bucket has been dumped, and when it is ready to be lowered for another load. The cross-head has now been elevated to the position shown, and the bucket actions are wide open. The bucket is now lowered onto the material to be loaded, the cross head moving downwardly toward the shaft 6 to the position shown in Fig. 7, and the toggle device assuming the folded position also shown in this figure. The lifting power is then applied to the hook block 15 and hoisting cable 14, and as the cross-head rises, the bucket sections turn on their supports on the shaft 6 and on the links 7 and 8 until they come to the closed positions shown in Fig. 1. During this closing action, the bucket sections have a powerful digging action due to the nature of the leverage applied thereto. The tripping lever 34 is next actuated, thereby moving the roller 27 out of holding contact with the latch 26. As soon as the latch is released the weight immediately causes the bucket sections to open and discharge their load. It will be noted that the ends of the flexible chains are attached to the bucket sections at points which are so located that, as the bucket opens, they move inwardly and downwardly about the axis of the rods 9. They thereby exert a pull of increasing leverage on the bucket sections in a direction tending to restrain the opening movement. This action is sufficient to steady the action and prevent too sudden opening.

The advantages of my invention will be apparent to those skilled in the art. Owing to the freely open space between the portions 7^a of the links 7, the hook block and hoisting cable can move freely therethrough and down to a position closely adjacent to the shaft 6. The opening and closing movement of the bucket is effected by a relatively short vertical movement of the cross-head. Therefore, the operation of the bucket requires very much less head room than has been required with the types of buckets heretofore in use.

The entire construction is simple and durable; the manner of attaching the cross-head to and disengaging it from the lifting shaft 6 is exceedingly simple and effective, the toggle device acting to guide and steady the movements of the parts. The form of the links 7, 7^a gives an effective method of suspending the bucket sections so that they can exert a powerful leverage action. This construction also reduces the total height of the bucket, and provides for the free operation of the cable and cross-head. The flexible members 18 provide simple means for preventing a too violent opening of the bucket and for taking up shocks. I do not consider, however, that these are a necessary element of my invention, as the bucket will operate in a very satisfactory manner without them.

It will be readily understood by those skilled in the art that the details of construction, such as the exact form of the lock, etc., may be varied without departing from the spirit and scope of my invention as defined in the appended claims.

I claim:

1. A hoisting bucket comprising a central lifting rod or shaft, two bucket sections pivotally swung from said rod or shaft at their upper inner corner portions, and link members pivotally connected with the upper outer corner portions of the bucket sections, said link members converging upwardly, and those at one side terminating in rigid laterally or horizontally bent portions to which the upper ends of the link members at the opposite side are pivotally connected at one side of the vertical center of the bucket; substantially as described.

2. A hoisting bucket having its bucket sections suspended at their upper inner corners from a central lifting rod or shaft, and having their outer corner portions swung upon depending links, the links at one side having rigid horizontally bent end portions extending past the vertical center of the bucket and to which the upper ends of the links at the opposite side are pivotally connected at one side of the vertical center of the bucket; substantially as described.

3. A hoisting bucket having its bucket sections suspended at their upper inner corners from a central lifting rod or shaft, and having their outer corner portions swung upon depending links, the links at one side having horizontally bent end portions extending past the vertical center of the bucket and to which the upper ends of the links at the opposite side are pivotally connected, and there being a free open space between said horizontally bent portions together with a hoisting cable having a hook block at its upper end, said block being movable down through the said open space; substantially as described.

4. A hoisting bucket, comprising a central lifting member, bucket sections connected thereto, a jointed frame to which the bucket sections are pivoted, a flexibly suspended cross-head movable within the frame toward and away from the lifting member, a hook block at the upper end of the cross-head suspension, said hook block being movable through the frame of the bucket to a position adjacent to the cross-head, said cross head having means for engaging and disengaging the lifting member, and guiding means for the cross-head, said guiding means forming a connection between the cross-head and lifting member independent of the frame and bucket sections; substantially as described. 70
5. A hoisting bucket, comprising a central lifting member, bucket sections connected thereto, a jointed frame to which the bucket sections are pivoted, a flexibly suspended cross-head movable within the frame toward and away from the lifting member, and having means for engaging and disengaging the same, and a jointed guide connecting the cross-head with the lifting member, said guide having its joint constructed to flex to permit the cross-head to move laterally but to hold said head substantially rigid with respect to endwise movement; substantially as described. 80
6. A hoisting bucket comprising a central lifting member, bucket sections connected thereto, a jointed frame to which the bucket sections are pivoted, a cross-head, a cable suspending the cross-head, a hook block at the upper end of the cable, said hook block being movable through the frame to a position adjacent to the cross-head, and latch means for engaging the cross-head with the lifting member; substantially as described. 90
7. A hoisting bucket comprising a central lifting rod or shaft, two bucket sections swung from their upper inner corners from the said rod or shaft, connected links on which the upper outer corner portions of the sections are swung, a cross-head having a latch device adapted to engage and disengage said rod or shaft, and a flexible shock-absorbing member connected to the sections and engaged with the cross-head, the ends of said device being attached to the bucket sections at points which move downwardly and inwardly about the axis of the outer pivots of said sections when the latter open; substantially as described. 100
8. A hoisting bucket comprising a central lifting member, bucket sections connected thereto, a jointed frame to which the bucket sections are pivoted, a cross-head, latch means for engaging the cross-head with the lifting member, and a flexible shock-absorbing member engaged with the cross-head and attached to the bucket sections at op- 110
- posite sides of the bucket sections at points which move downwardly and inwardly about the pivotal connection of the sections with the frame when the sections open; substantially as described. 120
9. A hoisting bucket comprising a central lifting rod or bar, bucket sections swung therefrom at their upper inner corner portions, jointed or link frames from which the upper outer corner portions of the bucket are swung, a cross-head movable freely to a position adjacent to the lifting rod or shaft, and a hoisting cable having a hook block at its upper end, said hook block being movable through the jointed or link frame; substantially as described. 130
10. A hoisting bucket having a central lifting rod or shaft, a bucket section pivoted thereto, a cross-head movable to a position adjacent to the lifting rod or shaft, and a toggle device having one member connected to the cross-head and the other member connected to the lifting rod or shaft; substantially as described. 140
11. A hoisting bucket comprising a central lifting rod or shaft, bucket sections swung therefrom, a cross-head movable to a position above and adjacent to the lifting rod or shaft, a latch hook carried by the lifting head, a coöperating latch device carried by the lifting rod or shaft, and a toggle device connected to the cross-head and the lifting rod or shaft; substantially as described. 150
12. A hoisting bucket comprising a central lifting rod or shaft, bucket sections swung therefrom, a cross-head movable to a position above and adjacent to the lifting rod or shaft, a latch hook carried by the lifting head, a coöperating latch device carried by the lifting rod or shaft, and a toggle device connected to the cross-head and the lifting rod shaft, said toggle device having means for controlling the operation of the latch; substantially as described. 160
13. A hoisting bucket comprising a central lifting rod or shaft, bucket sections swung therefrom, a cross-head movable to a position above and adjacent to the lifting rod or shaft, a latch hook carried by the cross head, a coöperating latch device carried by the lifting rod or shaft, and a toggle device connected to the cross-head and the lifting rod shaft, said toggle device having means for controlling the operation of the latch, together with a tripping lever carried by said toggle device; substantially as described. 170
14. A hoisting bucket comprising a central lifting rod or shaft, bucket sections swung therefrom at their upper inner end portions, connected links to which the upper outer end portions of the sections are pivotally connected, a cross-head movable vertically into a position between the sections when the latter are open, and a lifting cable connected to the cross-head and having a hook 180

block at its upper end, said hook block being movable downwardly between the connected links; substantially as described.

15. A hoisting bucket comprising a central lifting rod or shaft, bucket sections swung therefrom, a cross-head movable to a position above and adjacent to the lifting rod or shaft, a latch hook carried by the lifting head, a coöperating latch device carried by the lifting rod or shaft, and a toggle device connected to the cross-head and the lifting rod shaft, and a roller mounted on the toggle device and arranged to force the latch hook on the lifting head into engagement with the coöperative latching device, the shaft of said roller having a rolling bearing; substantially as described.

16. A hoisting bucket, comprising a central lifting member, bucket sections pivoted thereto, a jointed frame to which the bucket sections are also pivoted, a cross-head, latch means for engaging the cross-head with the lifting member, and a shock-absorbing means attached to the bucket sections at points which move downwardly and inwardly about the pivotal connections of the sections with the frame when the sections open, said

shock-absorbing means being also connected to a lifting element of the bucket; substantially as described.

17. A hoisting bucket having a central lifting member, two bucket sections pivotally swung at their upper inner corner portions from said member, link members pivotally connected with the upper outer corners of said sections at their lower ends and with each other at their upper ends; a cross-head over the lifting member and movable toward and from the same, latch means carried by the cross-head for engagement with the lifting member, and a flexible member engaged with the cross-head, at its central portion and connected at its end portions with the bucket sections through lever arms thereof which exert an increasing closing pull on the said sections as the latter open substantially as described.

In testimony whereof I have hereunto set my hand.

EDGAR E. BROSIUS.
